3 Claims. (Cl. 242—79)

The present invention relates to improvements in a device for shifting an empty spool and a coil wound spool in a reversible rolling mill and the like.

The device of the invention can be well adapted to a reversible rolling mill which is located at the central position and a winding device is provided on each side of the rolling mill to effect rolling operations, that is, once rolled strip is operated into the opposite direction by the reversed rotation of the press rolls to deliver the strip to the opposite direction for effecting the rolling again.

In a conventional coil shifting device, usually called a block type, a spool before rolling and after completing the rolling and also a coil wound spool have been transported by means of a crane so that it involved trouble in transporting empty spools and coil wound spools and also it accompanied dangers in carrying them by a crane.

The object of the invention is to obviate the above troubles and dangers accompanying to the transportation and taking out spools and coil wound spool by providing a turn table at middle position of the transporting stroke for carrying out the spool itself and coil wound spool, thereby providing a safety transportation device which can be easily handled.

For a better understanding of the invention, reference is taken to the accompanying drawings, of which:

FIG. 1 is an elevation of the present device as applied to a reversible rolling mill,

FIG. 2 is a diagrammatic plan view of FIG. 1 partly in section, and

FIG. 3 is an enlarged elevation of the turn table partly in section for illustrating its detailed portions more clearly.

Referring to the drawings, 1 represents a coil delivering apparatus of the coil after finishing the hot rolling and not wound around a spool 2, a coil rewinding frame which is driven by an electric motor 4 through a reduction gear 3, these members constituting a rewinding mechanism. Reference numeral 5 represents a stanchion of the rolling mill which supports the upper roll 6 and the lower roll 7 and the back-up rolls 8. Reference numeral 9 represents a steel band wound around a spool 10, which band is reciprocated between said rewinding mechanism to effect the odd number of rollings. FIG. 1 illustrates the operating condition of the rolling mill. Reference numeral 11 designates a coupling for connecting or disconnecting the spool 10 and the shaft 12, which is operated by means of a coupling cylinder 13. Reference numeral 14 represents an electric motor for transmitting a torque to the spool 10 through a reduction gear 15. Reference numeral 16 is a pawl for supporting the spool 10 arranged to be operated by a cylinder 17 to swing about a pivot 18. A first pawl pair is provided with a pawl 16 positioned at each side of the frame 19. Each pawl 16 is so arranged that when the spool 10 is disengaged from the shaft 12 by the action of cylinder 13 the pawl is turned clockwise by the action of the cylinder 17 to push out the spool 10 to be shifted on the frame 19. 20 represents a turn table having a supporting frame 21 formed thereon to support a vacant spool 10' or coil wound spool 10. Reference numeral 22 is a trunnion secured to the central portion of the frame of the turn table projecting downwardly from its lower surface and journaled in a bearing 23. Reference numeral 24 represents a fixed rail on which rest the rollers 25 pro-

2

vided for the turn table 20. On the inner periphery of the rail 24 is provided a rack 24' with which meshes a pinion 28 which is turned by a motor 26 through bevel gearing 27 so that the turn table 20 may be turned by operating the motor 26 through the pinion 28 meshing with the rack 24' on the inner periphery of the rail 24. A second pawl pair and a third pawl pair are provided on the turntable at the front and rear respectively. The pawls 29 of the second and third pawl pairs are positioned astraddle the front and rear supporting frame and each pawl is operated by a cylinder 30 to hold or eject spools 10, 10' respectively from the turntable in the same manner as previously explained in connection with the first pawl pair 16. Reference numeral 31 represents a part of the frame formed on the front and back of the turn table 20. The frame formed on the front and rear of the turntable is dimensioned to be aligned with frame A and frame 19 so that the spool 10 may be rolled into and out of the turntable 20 from the frame A or frame 19 when transferring spools.

In the above described device, when the spool 10 wound with a coil after the completion of rolling operation is disengaged from shaft 12 and shifted on the surface of frame 19 by the operation of the pawl 16 and is brought to the supporting frame 21 as shown by the broken lines in FIG. 1 by means of frame 31. On the other hand, on the rearward supporting frame is supported spool 10' which is loaded onto the turntable from the frame A. Under such condition the motor 26 is started to turn the turn table 20 for 180°, then the positions are interchanged. At this position the spool 10 is pushed out and into the frame 19 of the rolling machine by the action of the pawl 29 to complete the shifting. On the other hand, the spool 10' is brought to a position to be subjected to the rolling operation by the action of the pawl 29 through frames 31 and 19.

According to the invention, the shifting-in and -out of the spools 10 and 10' can be effected very easily by the provision of a turn table of simple construction.

Moreover, according to the invention, the forcing out of the spools 10 and 10' supported on the frame 21 can be effected by means of a pawl supporting these spools without necessitating additional complicated means.

Though the invention is described by means of an embodiment as shown in the drawing, yet various modifications can of course be made without departing from the scope of the claims.

What we claim is:

1. Apparatus for transferring loaded spools of steel strip which comprises a winding frame, a pair of pawls rotatably mounted in said frame, a spool rotatably mounted in said frame and restrainedly positioned within said frame by said pawls, means for rotatably driving said spool to load said steel strip on said spool, a turn table provided with a turn table frame, said turn table being mounted adjacent said winding frame with said turn table frame positioned to receive spools rolled from said winding frame, means for rotatably deflecting said pawls in said winding machine to transfer said loaded spool to said turn table, means including a second pair of pawls for holding said loaded spool on said turn table and for transferring said loaded spool from said turn table, means for rotating said turn table, and means including a third pair of pawls for transferring an empty spool on said turn table to said winding machine.

2. Apparatus for transferring a coil of rolled steel band delivered from a rolling mill which comprises a spool to take up said rolled steel band, a winding machine for driving said spool, means detachably coupling said spool to said winding machine, a pair of pivoted pawls tiltable about a respective pivot and positioned astraddle said spool to securely hold said spool within said wind-

ing machine, means for pivoting each of said pawls about said pivot to eject said spool from said winding machine, a turntable positioned adjacent the winding machine, said turntable including a pair of supporting frames, each of said supporting frames having a semicircular supporting portion, said turntable being positionable with one of said supporting frames positioned adjacent said winding machine to receive said loaded spool as it is ejected therefrom, said turntable being provided with a second pair of pivoted pawls tiltable about a respective pivot to secure said loaded spool within at least one of said supporting portions of said turntable after it has been transferred from said winding machine, and means for rotating said turntable.

3. Apparatus in accordance with claim 2 in which each pawl of said second pair of pivoted pawls comprises a

bifurcated pivoted pawl, a hydraulic actuating cylinder pivotally connected to one arm of said pawl, said cylinder being actuatable from a first position in which one of said arms restrainably holds said received spool within said turntable to a second position in which the other of said arms engages said spool to move said spool from said turntable.
